CLAIM

The ornamental design for a slit lamp for examining the structure of a patient's eye, substantially as shown and described.

DESCRIPTION

FIG. 1 is a right front perspective view of a slit lamp for examining the structure of a patient's eye showing my new design;

FIG. 2 is a left side perspective view thereof;

FIG. 3 is a rear perspective view thereof; and

FIG. 4 is a front perspective view thereof.
The bottom of the design is substantially plain and unornamented.

Fig. 3
